John F. Keller
By Daniel Brock, Attorney.

UNITED STATES PATENT OFFICE.

JOHN F. KELLER, OF MARTINSBURG, WEST VIRGINIA.

GRAIN-DRILL.

SPECIFICATION forming part of Letters Patent No. 257,951, dated May 16, 1882.

Application filed December 8, 1881. (No model.)

To all whom it may concern:

Be it known that I, JOHN F. KELLER, a citizen of the United States, residing at Martinsburg, in the county of Berkeley and State of West Virginia, have invented certain new and useful Improvements in Grain-Drills and other Seed-Planters, of which the following is a specification, reference being had therein to the accompanying drawings.

10 My invention consists of a novel construction of feed-roller for grain-drills, the same having a non-elastic and non-corrosive roller-surface detachable from the heads of the roller, and in other improvements, all of which will be understood from the following description.

15 In the accompanying drawings, Figure 1 is a rear view of the feed-box and feed-roller. Fig. 2 is a bottom view, showing both rollers. Fig. 3 is a cross-section on the line *x x*, Fig. 1. 20 Fig. 4 is a longitudinal section of the complex roller on lines *y y*, Fig. 2.

In my improved grain-drill I propose to use one elastic roller and one non-elastic and non-corrosive roller, preferably of glass.

25 The novelty of my invention is chiefly shown in the roller represented in Fig. 4.

In my machine are employed the usual standards, *A A*, supporting two axles or shafts, *B B*, one of which carries a common rubber feed-30 roller, *C*, working under the box *D* in the usual manner.

My improved roller is hollow, and consists

of a flat ring of glass, *E*, and two cast-iron heads or disks, *F*, held in place by bolts *G* and fastened to the shaft *B* by thumb-screws *H*. 35 These heads *F* have flanges to receive and hold the roller-surface or ring *E*, and lugs or projections *I* (preferably cast on the heads) prevent the parts from turning on each other when the bolts *G* are screwed up tight.

40 The non-elastic surface of the roller may be made of other non corrosive substances, yet I prefer glass.

The advantages of my roller are, first, the feed is uniform, whereas two rubber rollers or 45 iron rollers often become rough, and are then liable to feed two layers of grain instead of one. Also, my hollow roller is easily repaired, the surface being removed when worn and a new surface put in its place.

50 Having described my invention, what I claim is—

In a seeder or fertilizer-distributer, the glass-surfaced feed roller or ring *E* and the adjustable disks *F*, having a groove to receive the edge 55 or projecting ends *I* of the roller, in combination with the elastic roller *C*, substantially as set forth and shown.

In testimony whereof I affix my signature in presence of two witnesses.

JOHN F. KELLER.
